UNITED STATES PATENT OFFICE

ALFRED CROSSLEY, OF WASHINGTON, DISTRICT OF COLUMBIA, ASSIGNEE TO WIRED RADIO, INC., OF NEW YORK, N. Y., A CORPORATION OF DELAWARE

PIEZO-ELECTRIC CRYSTAL OSCILLATOR

Application filed May 26, 1926. Serial No. 112,362.

My invention relates broadly to the generation of electrical oscillations and more particularly to a circuit arrangement for a piezo electric crystal controlled electron tube oscillator.

One of the objects of my invention is to provide a circuit arrangement for a piezo electric crystal controlled electron tube oscillator by which the high potential direct current supply system may be segregated from the circuit in which high frequency oscillations are produced for permitting the adjustment of the oscillating circuit independently of the high potential supply system.

Another object of my invention is to provide a circuit arrangement for a piezo electric crystal controlled electron tube oscillator system which may be readily coupled with a power amplifier system without resort to the employment of stopping condensers, associated grid leaks or choke coil systems.

My invention has been illustrated in detail in the accompanying drawings which will be understood more clearly from the specification hereinafter following.

In the drawings Figure 1 diagrammatically illustrates the circuit arrangement of my invention and Fig. 2 shows a modified circuit arrangement wherein the piezo electric control element is in slightly different arrangement with respect to the electrodes of the electron tube system.

In controlling an electron tube system by a piezo electric crystal element I have found that special provision must be made in the electron tube oscillator circuits for securing high efficiency in the generation of high frequency oscillations. For the proper functioning of a piezo electric frequency control system a relatively high potential is supplied to the plate circuit of the electron tube system. It is not unusual to employ 1,000 volts on the plate circuit of an electron tube having a rating of approximately 150 watts. The high frequency oscillations corresponding to the frequency of the piezo electric crystal which is associated with the electron tube system are by my circuit arrangement made to occur

in a circuit independent of the output circuit of the electron tube system. I provide a parallel feed system from the piezo electric controlled electron tube system to the high frequency oscillation circuit. The oscillation circuit is not connected in series with the output circuit of the electron tube system as has been customary heretofore in the art but is connected in parallel with the electron tube system entirely independent of the high potential supply. Parts of the high frequency oscillation circuit are maintained at ground potential and in this way adjustment may be made from time to time without subjecting the operator to injury from the high potentials which are present. The separate high frequency oscillation circuit facilitates the coupling of the frequency control system and oscillator to a power amplification system. A direct connection may be made from points along the inductance of the high frequency oscillation circuit to the grid circuit of the power amplification system for thus obtaining the required controlling voltage without resort to the use of stopping condensers and their associated grid leak or choke coil systems.

Referring to the drawings in more detail reference character 1 designates the piezo electric crystal which is positioned between contact plates 1^a and 1^b which are connected across the grid and filament electrodes of the electron tube 4. In order to place the proper potential upon the piezo electric crystal element 1 I provide a high frequency choke coil 2 and a battery 3 for normally biasing the piezo electric crystal circuit for permitting the crystal to operate at substantially no load, as has been described more fully in my copending application, Serial Number 26,968, filed April 30, 1925, now Patent 1,696,626 of December 25, 1928. The output circuit of the electron tube 4 includes the plate and filament electrodes connected in series with a high potential source 6 through high frequency choke coil 5. A condenser 7 is provided for by-passing the high frequency current from the high voltage direct current circuit. Radio frequency by-pass condenser 100

8 provides a path over which the generated radio frequency currents are transferred to an independent high frequency oscillation circuit which consists of an inductance 9, a variable condenser 10 and an ammeter 11. The frequency control system is grounded as represented at 12, and it will be observed that one terminal of the inductance 9 and one side of the condenser 10 are at ground potential and in such condition can be safely handled by an operator during the process of adjustment. This condition, particularly with respect to the movable plates of the variable condenser 10 is ideal for the manipulation of the tuning feature of the circuit without injury to the operator. In systems heretofore employed where the high frequency oscillation circuit is series connected in the output circuit substantial insulation has been necessary for the parts of the oscillation system and extreme precaution has been required in the adjustment of the circuits for avoiding severe shock due to the fact that when touching either the inductance or the condenser another path to ground is provided through the operator's body by which the high voltage direct current will flow. In my arrangement the tuned circuit is so situated that only high frequency current flows in that circuit and one terminal of either the inductance or the condenser can be touched by the operator during the process of tuning without any disastrous effect.

By virtue of the absence of high voltage direct current in the tuned circuit 10 and 11, a direct connection to the grid circuit of the power amplifying system may be readily made and the required controlling voltage is thus obtained without the introduction of stopping condensers, associated grid leaks or choke coil systems.

As represented in Fig. 2 the piezo electric crystal element may be positioned between the plate and grid electrodes of the electron tube 4. By this arrangement a change in the reactance nature of the tuned circuit takes place. In Fig. 1 the tuned circuit 9, 10 and 11 is so tuned that it affords an inductive reactance for the frequency to which the circuit is oscillating. In Fig. 2 the tuning should be such that the tuned circuit affords a capacitive reactance for the frequency at which the circuit is oscillating. This condition is brought about by the location of the piezo electric substance in the circuits and the resultant change in phase relationships of the two circuits to produce a condition of oscillation.

60 The numerous advantages arising out of the parallel feed system constructed in accordance with my invention will be readily understood from the description herein.

While I have described my invention in certain preferred embodiments, I desire it

to be understood that modifications in detail may be made and that no limitations upon the invention are intended other than are imposed by the scope of the appended claims.

What I claim as new and desire to secure by Letters Patent of the United States is as follows:

1. In a frequency control system an electron tube having grid, filament and plate electrodes, input and output circuit interconnecting said electrodes, a high potential supply system connected in series with said output circuit, a radio frequency choke coil in series therewith, a piezo electric crystal element connected in series in said input circuit, to control the operation of said circuits, an independent radio frequency choke coil connected in said input circuit a high frequency oscillation circuit and connections from said output circuit to said high frequency oscillation circuit whereby high frequency oscillations corresponding to the natural frequency of said piezo electric crystal element are sustained in said high frequency oscillation circuit. 70 75 80 85 90

2. In a frequency control system an electron tube having grid, filament and plate electrodes, input and output circuits interconnecting said electrodes, a high potential source interposed in series in said output circuit and having means comprising a radio frequency choke coil for excluding high frequency oscillations therefrom, a piezo electric crystal element arranged in said input circuit, an independent radio frequency choke coil disposed in said input circuit means in said input circuit for fixing the potential of one side of said piezo electric crystal element, a high frequency oscillation circuit and parallel connections between points in said output circuit with said high frequency oscillation circuit whereby high frequency oscillations at the natural frequency of said piezo electric crystal element may be sustained in said high frequency oscillation circuit independent of said high potential source. 95 100 105 110

3. In a frequency control system an electron tube having grid, filament and plate electrodes, input and output circuits interconnecting said electrodes, a high potential source interposed in series in said output circuit and having means comprising a radio frequency choke coil connected between said plate electrode and said source for excluding high frequency oscillations therefrom, a piezo electric crystal element connected in said input circuit, means in said input circuit for fixing the potential of one side of said piezo electric crystal element, a radio frequency choke coil disposed between said means and the grid electrode of said electron tube a high frequency oscillation circuit, said circuit including inductance and capacity with one side of said inductance and capacity 115 120 125 130

at ground potential and parallel connections between said high frequency oscillation circuit and said output circuit whereby high frequency oscillations corresponding to the natural frequency of said piezo electric crystal element are sustained by said high frequency oscillation circuit.
